CUTTING TOOL

Joseph Fossa, Lynn, Mass., assignor to United Shoe Machinery Corporation, Borough of Flemington, N. J.

Application October 20, 1939, Serial No. 300,415

6 Claims. (Cl. 30—294)

This invention relates to cutting tools and is herein illustrated as embodied in a tool for cutting lacing threads of shoes.

In the manufacture of shoes of various types, in which shoe laces are used as closures, it is common practice to lace the quarter portions of the upper together by means of threads before the upper is assembled on the last. After the lasting and other operations necessary to complete the shoe have been performed, the lacing threads are cut to facilitate removal of the last from the shoe.

It is an object of the present invention to provide a tool for cutting such lacing threads which will be particularly effective to cut the thread rapidly without likelihood of injuring the shoe. To this end and as illustrated, I have provided a thread cutting tool comprising a shank terminating in a hook portion having an inwardly disposed cutting blade provided with a projection extending beyond the blade for engaging the shoe to guide the blade between the parts of the upper, and a guard extending into the proximity of the blade adjacent to the shoe-engaging portion. Preferably, the guard extends a sufficient distance laterally of the blade such that the blade cannot be brought into contact with the upper of the shoe in such a way as to damage it.

These and other features of the invention will be apparent from the following detailed specification, taken in connection with the accompanying drawing, and will be pointed out in the claims.

In the drawing,

Fig. 1 is a side view of one form of my thread cutting tool with a shoe positioned in operative relation to it;

Fig. 2 is a side view, partly in section, on an enlarged scale, of the end portion of the tool illustrating the operation thereof; and

Fig. 3 is a cross sectional view taken along line III—III of Fig. 2.

The thread cutting tool comprises a shank 10 terminating in a hook portion 12 and having an inwardly disposed blade 14 terminating in a cutting edge 16. At the end of the blade is a rounded shoe-engaging portion 18, which has a nose portion 20 extending slightly beyond the edge of the blade. The construction thus far illustrated would be effective to cut lacing threads, such as threads 22 securing together the quarters 24 of a shoe 26, it being merely necessary to insert the nose portion 20 of the tool beneath the lowermost loop of the lacing thread and to draw the tool upwardly along the tongue 28 of the shoe, the nose portion being effective

to pick up the threads to be severed upon engagement with the cutting edge 16.

In order to prevent any likelihood of the blade cutting into the quarter or other parts of the upper, I have provided a guard 30 in the form of a plate secured to a bracket 32 slidably mounted upon the shank 10. The guard is secured to the bracket by screws 34 extending through elongated slots 36, thus to permit adjustment of the guard transversely of the shank 10. The bracket with the guard can be moved along the shank 10 and secured in adjusted position by a set screw 38. The forward portion of the guard is curved, as indicated by reference character 40, to provide for the guiding of the threads toward the cutting edge 16.

Preferably, the guard 30 is adjusted into a position, such as that shown in Fig. 2, in which the guard is spaced to provide some clearance between the blade and the guard, with the curved portion 40 of the guard located immediately in back of the nose portion 20 to provide for entrance of the threads between the guard and blade. It is to be noted (Fig. 3) that the guard extends sufficiently on opposite sides of the blade 25 ordinarily to prevent the blade from contacting with the edges of the quarter in operation of the tool upon shoes. Moreover, the lower portion of the guard 30 is provided with a V-shaped notch 42 so related to the cutting edge 16, that the guard, if desired, can be adjusted into position such that the blade will extend part way into the notch. With the parts in either of the positions mentioned, there is little likelihood that the edges of the shoe quarters can engage the cutting edge 35 and be damaged.

It is contemplated that this tool can be used as a hand tool. However, preferably, and as herein shown, the tool is secured to a last pulling machine generally indicated by reference character 46, the shank 10 being held in a bracket 48 on the machine by a set screw 50.

In the use of the device the shoe is presented to the tool in such manner that the nose portion 20 of the shoe-engaging member is positioned 45 beneath the lowermost loop of the lacing thread to be cut. The shoe is then moved along the tool with the tongue portion of the shoe maintained in contact with the nose 20, with the result that the nose 20 successively picks up the 50 loops 22, and the curved portion 40 of the guard serves to guide the loops into engagement with the cutting edge 16, which severs them.

Thus it will be seen that the invention provides a comparatively simple tool which is effective 55

to cut lacing threads without likelihood of damage to the upper of the shoe.

Having described my invention, what I claim as new and desire to secure by Letters Patent of the United States is:

- 5 1. A thread cutting tool comprising a shank terminating in a hook portion, a cutting edge disposed upon the inner side of the hook portion, a shoe-engaging portion projecting from the hook portion and extending beyond the cutting edge, and a guard carried by the shank and extending into juxtaposition to the cutting edge.
- 10 2. A thread cutting tool comprising a shank terminating in a hook, a cutting blade disposed inwardly of the hook, a shoe-engaging member extending beyond the outer end of the cutting blade, and a guard positioned adjacent to the blade in back of the shoe-engaging member and having a curved portion for guiding lacing 15 threads to the cutting blade.
- 15 3. A thread cutting tool comprising a shank terminating in a hook, a cutting blade disposed inwardly of the hook, a shoe-engaging member extending beyond the outer end of the cutting blade, a guard positioned adjacent to the blade in back of the shoe-engaging member, and means 20 for varying the position of the guard relatively to the blade and to the shoe-engaging member.

4. A thread cutting tool comprising a shank terminating in a hook having an inwardly disposed cutting blade, a shoe-engaging member extending beyond the outer end of the blade, a guard mounted upon the shank and extending 5 into the proximity of the blade, and means for mounting the guard for adjustment along the blade to space the guard from the shoe-engaging member.

5. A thread cutting tool comprising a shank 10 terminating in a hook having an inwardly disposed cutting blade, a shoe-engaging member extending beyond the outer end of the blade, a guard mounted upon the shank and having a portion extending along the blade in back of the 15 shoe-engaging member, and means for adjustably spacing the guard from the blade.

6. A thread cutting tool comprising a shank terminating in a hook, a cutting blade disposed inwardly of the hook, a guard located upon the 20 shank and having a portion extending into the proximity of the blade and extending transversely of the blade on opposite sides thereof, said portion having a groove located opposite to the edge of the blade, and means for varying 25 the position of said portion relatively to the blade.
